UNITED STATES PATENT OFFICE

101,798

DESIGN FOR A CRAVAT HOLDER

Charles Silverman, Providence, R. I.

Application September 25, 1936, Serial No. 65,000

Term of patent 7 years

To all whom it may concern:

Be it known that I, Charles Silverman, a citizen of the United States, residing at Providence, in the county of Providence and State of Rhode Island, have invented a new, original, and ornamental Design for Cravat Holders, of which the following is a specification, reference being had to the accompanying drawing, forming part thereof.

The particular initials shown in the drawing are for the purpose of illustration only.

I claim:

The ornamental design for a cravat holder, substantially as shown and described.

CHARLES SILVERMAN.
